COMB AND BRUSH SET

Felix Kapelman, Bronx, N. Y., assignor to The Glemy Company, Inc., New York, N. Y., a corporation of Delaware

Application March 3, 1939, Serial No. 259,500

7 Claims. (Cl. 132—85)

This invention relates to improvements in combined comb and brush sets and has for one of its objects to provide an improved device of simple and practical construction wherein a comb and brush are so connected that the teeth and bristles thereof may be arranged relative to each other for simultaneous use, or may be separated so that either may be used individually.

Another object is to encase a comb and brush within a holder, wherein said comb and brush are releasably held by cooperating elements, one of which extends through a portion of said holder from which said element may be withdrawn by a relative movement between other portions of the holder.

The above and other objects will appear more clearly from the following detailed description when taken in connection with the accompanying drawings which illustrate preferred embodiments of the inventive idea.

In the drawings:—

Figure 1 is a perspective view of a combination comb and brush set constructed in accordance with the invention and showing the teeth of the comb and bristles of the brush arranged in juxtaposition.

Figure 2 is a vertical transverse section on the line 2—2 of Figure 1, the dotted lines indicating the position to which the brush may be adjusted relative to the comb when it is desired to use either of the elements individually.

Figure 3 is a perspective view, similar to Figure 1, showing the brush and comb adjusted for individual use.

Figure 4 is a section substantially on the line 4—4 of Figure 1.

Figure 5 is a perspective view of a comb and brush set showing another form of the invention.

Figure 6 is a perspective view of the comb shown in Figure 5.

Figure 7 is a similar view of the brush of Figure 5.

Figure 8 is a perspective view of a comb and brush set illustrating still another form of the invention in which the comb and brush are encased within a holder or housing.

Figure 9 is an end elevation of the holder shown in Figure 8, the dotted lines indicating an adjustment of a portion of the holder which permits of the release of the comb or brush from the housing.

Figure 10 is a perspective view, similar to Figure 8, and showing the comb adjusted to operative position.

Figure 11 is a section substantially on the line 11—11 of Figure 10.

Figure 12 is a section substantially on the line 12—12 of Figure 10, but showing both the comb and brush adjusted to operative positions alongside each other, and,

Figure 13 is an end elevation of the device of Figure 8 showing the comb and brush in operative positions.

Referring more particularly to Figures 1 to 4, the device herein shown comprises a comb consisting of the back 15 which may be made of any desired stock, and which has extending from one edge thereof the usual teeth 16. Associated with this comb is a brush consisting of the back 17 and the single longitudinal row of bristles 18. In accordance with the present invention and the embodiment now being described, these two separate elements, namely, the comb and brush are permanently interconnected by a tubular pivot 19 which has its ends swaged to engage the outer faces of the backs 15 and 17, the inner faces thereof being in abutting relation. With the comb and brush thus connected and arranged in the position of Figures 1 and 2, the bristles 18 will be disposed along the teeth 16 of the comb in close proximity thereto so that said bristles will be effective in brushing the hair as the comb is employed. To releasably retain the elements in the position just referred to, one of them, such as the back 17 of the brush, may be provided adjacent each end thereof and in its inner face with recesses 20 into which extend the studs 21 formed on the inner opposed face of the back 15 of the comb. When so engaged, the two backs 15, 17 are frictionally retained in position, but may be released from said position by a relative movement of one of the backs about the pivot 19, the material of said backs having sufficient resiliency to permit of the studs 21 riding out of the recesses when said pivotal movement is effected. Thus, as shown in Figure 3, the brush may be turned about the pivot 19 to a reverse position from that shown in Figure 1 with the teeth 16 and bristles 18 separated from each other and extending in opposite directions. The backs 15 and 17 are also frictionally held in such position by engagement of the studs 21 in the recesses 20 in the reverse position of Figure 4.

In the form of the invention shown in Figures 5 to 7, the back 22 of the brush has projecting from its inner face adjacent one end thereof the headed stud 23, while at its opposite end said back is provided with a longitudinally extending slot 24 in which is pivotally mounted a latch 25. The back 26 of the comb is provided in each end thereof with the notches 27 and 28, the former of which is adapted to receive the shank of the stud 23, while the notch 28 receives the shank of the latch 25, when the comb and brush are assembled, as in Figure 5, with the bristles of the brush arranged alongside the teeth of the comb. In this manner the two elements are releasably maintained in cooperative relation and when it is desired to use either of them individually, the 60

latch 25 may be swung about its pivot so as to be disengaged from the notch 28, whereupon the comb 27 may be swung about the stud 23 as a pivot, or may be completely detached from the brush.

The form of the invention shown in Figures 8 to 13 provides for encasing the comb and brush 29 and 30 within a holder or housing, generally indicated by the numeral 31, and for mounting the same therein in such manner that either or both may be swung to positions wherein the teeth and bristles thereof may be employed for combing and brushing operations.

The housing 31 is made of any suitable material having a degree of flexibility, such as Celuloid or the like, and comprises two side walls 32 and 33 which combine with an intermediate partition or wall 34 to form compartments for receiving the comb and brush. These latter elements are permanently connected to the housing by a common pivot 35 which extends through the walls 32, 33, 34 and through the backs of the comb and brush 29 and 30. The upper edges of the walls 32, 33 and 34 are notches as indicated at 36 so that the backs of the comb and brush may be grasped to swing the same about their pivot 35, as indicated by the position of the comb in Figure 10. One end wall 37 of the housing is reduced at its upper end as indicated at 38 to form a shoulder upon which the backs of the comb and brush will rest when the same are swung to their operative positions, as best shown in Figures 10 and 13. The other end wall of the housing is formed by the two overlapping flaps 39 and 40 which are pivotally connected together at 41 for a purpose which will presently appear.

To releasably retain the comb and brush within the housing, the back of the brush 30 is provided upon its inner face and adjacent one end thereof with a stud 42 which projects through an opening 43 formed in the intermediate wall 34, and into an opening or recess 44 in the inner face of the comb back 29, as shown in Figure 11. This interengagement of the parts prevents inadvertent swinging of either the comb or brush about its pivot, but when it is desired to adjust either of said elements to operative positions the stud 42 may be withdrawn from the recess 44 and the opening 43 by an initial outward or separating movement of the portion of the wall 33 adjacent the end wall formed by the flaps 39 and 40. This lateral or outward movement of the wall 33 is accomplished by exerting inward pressure upon the lower portion of said wall adjacent said end wall, whereupon there will be a pivotal movement of the wall 33 and its end flap 39 about the pivot 41, as indicated by the dotted lines in Figures 9 and 11. This separation of the wall 33 from the wall 34 adjacent the top of the housing permits of the back of the brush being shifted laterally outward so as to withdraw the stud 42 from the recess 44, whereupon either the brush or the comb may be swung about the pivot 35 to the operative position thereof. The resiliency of the material of which the wall 33 is formed permits the same to restore to its normal position after pressure thereon is relieved.

What is claimed is:

1. In combination, a comb having a back, a brush also having a back, cooperating means between the backs of said comb and brush for piv-

otally connecting the same together, and further cooperating inter-engaging means on opposed portions of said backs for releasably retaining the teeth of the comb and bristles of the brush in juxtaposition to each other, the disengagement of the last named cooperating means permitting relative pivotal movement between said comb and brush. 5

2. In combination, a comb and a brush each having backs arranged alongside each other, means pivotally connecting said backs so that the same may be adjusted to a position with the teeth of the comb and bristles of the brush contiguous to each other and also to a position wherein said teeth and bristles are spaced from each other and extend in opposite directions, and cooperating means between said backs for releasably retaining the same in the first named position.

3. In combination, a comb having a back, a brush also having a back, a pivot extending transversely through said backs intermediate the ends thereof, and means near adjacent ends of said backs for releasably retaining the latter elements with their teeth and bristles in juxtaposition. 25

4. In combination, a comb having a back, a brush also having a back, a stud on one of said backs adjacent an end thereof, a notch formed in the other back for receiving said stud and pivotally connecting said backs together, a latch pivoted to the other end of the first named back, and a second latch formed in the adjacent end of said other back for receiving said latch whereby said backs are maintained in juxtaposition with their teeth and bristles adjacent each other. 35

5. In combination, a comb and a brush, cooperating means on said comb and brush for pivotally connecting the same, a latching member carried by one of said elements, and means formed in the other element for releasably receiving said latching member to retain said comb and brush in position with their teeth and bristles adjacent to each other. 40

6. In combination, a comb and a brush, a casting therefor having side and intermediate walls forming separate compartments for receiving said comb and brush, a common pivot for said comb and brush extending through said walls, cooperating means on said comb and brush for releasably maintaining the same encased within their respective compartments, and means connecting said side walls for relative movement therebetween so that said cooperating means may be rendered ineffective to permit of relative pivotal movements between said comb and brush. 50

7. In combination, a comb and a brush, a casting therefor having side and intermediate walls forming separate compartments for receiving said comb and brush, a common pivot for said comb and brush extending through said walls, a recess formed in one of the first named members, a stud on the other member projected through said intermediate wall for engagement in said recess to releasably maintain said comb and brush members encased within their respective compartments, and means to pivotally connect said side walls so that the same may be spread apart sufficiently to disengage said stud from said recess whereby relative pivotal movement between said comb and brush may be effected. 60
